PHONOGRAPH RECORD ALBUM OR THE LIKE

Rudolph A. Froehlig, Little Neck, N.Y., assignor to Modern Album and Finishing, Inc., College Point, N.Y., a corporation of New York

Filed Feb. 15, 1966, Ser. No. 1,054

Term of patent 14 years

(Cl. D59—8)

FIG. 1 is a front perspective view of a phonograph record album, showing my new design;

FIG. 2 is another perspective view thereof;

FIG. 3 is a rear elevational view thereof on a reduced scale;

FIG. 4 is a side elevational view thereof on an enlarged scale;

FIG. 5 is a side elevational view of the side opposite that shown in FIG. 4; and

FIG. 6 is a top plan view thereof.

The characteristic features of the present invention reside in a phonograph record album having a square smaller jacket in one corner of a square larger jacket with the mouth of each substantially on the same plane.

I claim:

The ornamental design for a phonograph record album or the like, substantially as shown and described.
